UNITED STATES PATENT OFFICE.

ELIS F. STENMAN, OF WORCESTER, MASSACHUSETTS, ASSIGNOR, BY MESNE ASSIGNMENTS, TO INDEPENDENT BUTTON FASTENER MACHINE COMPANY, (INC.), OF BOSTON, MASSACHUSETTS, A CORPORATION OF MASSACHUSETTS.

BUTTON-SETTING MACHINE.

1,092,604.

Specification of Letters Patent.

Patented Apr. 7, 1914.

Application filed June 10, 1912. Serial No. 702,693.

To all whom it may concern:

Be it known that I, ELIS F. STENMAN, a citizen of the United States, residing at Worcester, county of Worcester, Commonwealth of Massachusetts, have invented certain new and useful Improvements in Button-Setting Machines, of which the following is a specification.

This invention relates to button fastening machines, being in the nature of an improvement upon my application serially numbered 679,361, filed February 23, 1912.

The object of this invention is to provide dies of such conformation as will accomplish certain desired results in the button setting operation.

In the dies shown in the above mentioned application and indeed in all dies for this purpose which are known to me, there is no provision made for smoothing or rounding off the edges of the wire that clamps the button to the material. In this invention, I have sought to produce dies which will set the button securely and yet leave no exposed edges or corners on the wire. Various other features are also included in my invention, all of which tend to produce the desired neatness and finish, and the smoothness of operation of the machine. All of these features will be more fully set forth in connection with the construction and operation of a device embodying my invention, and will be described in the specification which follows and which is shown as an illustrative embodiment in the accompanying drawings.

In these drawings which accompany and form a part of the specification,—Figure 1 is a fragmentary plan view, similar to Fig. 1 of the above mentioned application, showing my preferred construction. Fig. 2 is a vertical section on the line 2—2 of Fig. 1. Fig. 3 is a partial plan section on the line 3—3 of Fig. 2. Fig. 4 is a section on line 4—4 of Fig. 1. Figs. 5, 6 and 7 are enlarged views showing the action of my improved dies.

The forming dies which shape the staple and set the button are indicated at 62, 63 and 64. These dies, as in my prior application, are slidably mounted within the guide walls 1 and 2 and upon a supporting block 3, which form part of the frame of my machine. Their means of operation may be

by any suitable mechanism, as for example that illustrated in my former application. The wire 6 is fed through the block 1¹ and across the face of the dies 62, 63 and 64. The grooves *y*, *y*, in the dies 62 and 64 are of sufficient depth to completely house the wires 6, and are chamfered on their near ends to facilitate the forward movement of the wire. In front of the wire 6 is the forming block 77 and setting block 120, the latter being made adjustable, as will be later explained. The dies 62 and 64, in addition to the grooves *y*, are also provided with longitudinal grooves *z*, as in my previous application, but with the difference that these grooves are somewhat farther extended along the inner face of the dies 62 and 64 and are adapted to receive the tongues *x*¹ which are formed along each side of the central die 63. This tongue and groove arrangement is twofold. It forms a lock for the three dies, preventing any vertical disarrangement, and furthermore the tongues *x*¹ serve as valuable adjuncts in the special operation of the die 63.

It will be noticed that the central die 63 instead of having a square nose as before is slightly beveled rearwardly toward the center, as at 63¹, and is further grooved horizontally at *x*² to compel the wire 6 to assume the form shown in Figs. 6 and 7. The central groove *x*³ is the same as previously shown and is provided to receive the shank S of the button B, the latter being fed in any suitable manner into stapling position with the wire 6. When the button B is in position to receive the wire, it will be noticed that the shank S is not entirely protected by the groove *x*³. As a consequence, there is a possibility of the wire 6 when it is advanced through the loop of the shank S causing a slight dislodgment of the button. This would interfere with or entirely prevent the proper placing of the wire within said shank. To obviate these difficulties, I provide a covering plate 10 which is extended so that its forward edge slightly overreaches the face of the dies 62, 63 and 64 in their retracted position. A central groove 10¹ which registers with the groove *x*³, serves not only to guide the shank S as it approaches the position shown, but to maintain it in desired relation to the wire 6 after it has reached this position. After the wire

has been fed through the shank of the button the initial movement of the forward part of the die severs the section of wire which has entered the groove y . By making this groove y deeper than before, I insure a certain maintenance of the wire 6 in its proper relation to the dies and to the forming block 77 which is then to rise to operative position as in my previous application.

10 When the dies have sufficiently advanced to imprison the shank S between the rib of the forming die 77 and the wire 6, the further movement of the dies causes a gradual bending and turning of the severed wire 6 until it assumes the conformation illustrated in Fig. 6. It will be noticed in this figure that the dies 62 and 64 have made an independent advance, while the die 63 has remained temporarily stationary. The forming block 77 is now retracted from the path of the dies which will then be advanced against the setting block. In making this advance the turned ends 6^1 are securely held within the grooves x , x , and 25 against the ends of the tongue x^1 . The loop 6 ^{2} which surrounds the shank S is seated within the recesses x^2 of the die 63. In this way, I effectually guard against a displacement of the bent wire during its advance upon and penetration through the material 30 U, which is to be operated upon. In the clenching operation it will be noticed that the outer corners of the die 63 and the forward ends of the tongues x^1 serve to clench the turns of the wire closely and firmly 35 upon the material U, thus tending to present a smoother and neater exterior than would be the case if this wire were simply folded upon the outside of the material as 40 shown in my previous application. It will thus be seen that my improved machine not only guarantees accuracy of movement, but superior finish in the work.

In the drawings, I have illustrated the 45 clenching wire 6 as a round conformation. It is quite apparent that dies similar in shape to those here set forth could be employed to manipulate flat or oval, or indeed, any suitably shaped wire, more easily than 50 the ordinary dies now in use. Furthermore, with these improved dies and protecting plate 10, it is possible for me to employ my machine for the use of buttons which have

their shanks swivel-mounted, such as certain forms of pearl headed buttons now in 55 use in the trade.

To further insure the proper finish and accuracy of the completed work, I prefer to mount the setting block 120 in sliding ways upon a bracket 12 secured to the frame of 60 my machine. A threaded thumb screw 13 rotatably mounted in the block 12 and held in position by a collar 14 affords a delicate adjustment of the setting block 120. With these adjustments, it is possible to vary the 65 clenching effect of my new die 63 without in any way changing the position or operating means of the die.

Various modifications in the construction and operation of my machine as herein set 70 forth, may obviously be made, all without departing from the spirit of my invention if within the limits of the appended claims.

What I therefore claim and desire to se- 75 cure by Letters Patent is:

1. In a machine for the setting of buttons and the like, a series of forming dies, one of said dies having a longitudinal groove therein to receive the shank of a button, and a covering plate having a groove 80 registering with said groove to guide and maintain the button in proper position.

2. In a button setting machine of the wire feed type, a series of forming dies, the intermediate die of said series having lateral tongues formed thereon and having a nose beveled rearwardly and a recess extending transversely thereof, the lateral dies each having a transverse groove to house a wire 90 and a longitudinal groove to receive said tongues of the intermediate die, said intermediate die having a longitudinal groove to receive and guide a button shank, and a cover plate having a groove registering 95 with said longitudinal groove of said intermediate die and effective to assist in guiding and centering the button and shank in its advance to the wire and to hold said shank firmly against the wire. 100

In testimony whereof I affix my signature in presence of two witnesses.

ELIS F. STENMAN.
